UNITED STATES PATENT OFFICE.

JOHN A. McCOACH, OF BOICOURT, KANSAS.

PERMUTATION-LOCK.

1,166,233.

Specification of Letters Patent. Patented Dec. 28, 1915.

Application filed April 26, 1915. Serial No. 23,917.

To all whom it may concern:

Be it known that I, JOHN A. McCOACH, a citizen of the United States, residing at Boicourt, in the county of Linn and State 5 of Kansas, have invented certain new and useful Improvements in Permutation-Locks; and I do declare the following to be a full, clear, and exact description of the invention, such as will enable others skilled in the art 10 to which it appertains to make and use the same.

My invention relates to improvements in locks and latches and more particularly to the former of the permutation type.

15 The object of the invention is to provide a lock of this class possessing as few parts as possible, yet one which although of such simple construction will be highly efficient in operation and will possess a number of 20 advantageous features.

With this general object in view, the invention resides in certain novel features of construction and in unique combinations hereinafter fully described and claimed and 25 shown in the drawing wherein like reference characters designate corresponding parts throughout the several views and wherein:

Figure 1 is a sectional view of a lock constructed in accordance with my invention 30 with the bolt projecting and retracting means therefor in inactive position; Fig. 2 is a similar view showing such retracting means disposed for retracting the bolt; Fig. 3 is a horizontal section as seen along the 35 plane indicated by the line 3-3 of Fig. 1; Fig. 4 is a disassembled perspective view of the bolt retracting means, and Fig. 5 is a similar view of the bolt.

In this drawing which constitutes a part 40 of the application, the numeral 1 designates a flat rectangular casing which may be constructed in any preferred manner, one end wall of this casing being shown in the present embodiment of the invention as provided 45 with a rectangular opening 2 through which the outer beveled end 3 of a horizontally disposed locking bolt 4 is normally projected. The bolt 4 is provided at a suitable point, shown in the drawing upon its lower 50 side, with a stop 5 which abuts one end wall of the casing and limits the outward movement of said bolt as clearly disclosed in Figs. 1 and 2. The inner end of the bolt 4 is provided with a rearwardly extending neck 6 formed integrally with and extending inwardly from the upper corner of its

inner end, said neck being provided on its under side, at the inner end thereof, with a pair of depending teeth 7 preferably beveled on one side as shown in Figs. 1, 2 and 60 5. The bolt 4 is normally projected through the opening 2 by any preferred type of spring 8 here shown in the form of a flat leaf spring secured at its lower end to the lower side of the casing 1, while its upper 65 end bears against the rear end of the bolt directly beneath the fixed end of the neck 6, the latter being normally forced downwardly into contact with the permutation bolt retracting means M by a suitable spring 70 9 interposed between said neck and the upper side of the casing 1.

The means M above mentioned comprises a shaft 10 which is passed transversely through the opposite sides of the casing 1 75 and which is provided with a knurled head 11 at one of its ends, the portion of the shaft immediately adjacent the inner side of said head being of polygonal formation as disclosed at 12, while the opposite end of 80 said shaft is threaded as clearly disclosed in Figs. 3 and 4. The polygonal portion 12 of the shaft 10 is passed through a polygonal opening in an indicating dial 13 having thereon a series of lettered or numbered 85 graduations, this dial being disposed adjacent the side of the casing 1 which is exposed to view when the lock is applied to use, and being adapted for coaction with an immovable indicator 14 which is secured 90 to this side of the casing as indicated in Fig. 3, it being evident that such indicator may be positioned at any desired point. Furthermore, it is to be understood that should the lock be mortised into the edge of 95 a door or the like, the dial 13 and indicator 14 will not be disposed immediately adjacent the side of the casing 1, but will be positioned on one side of the door.

The polygonal portion 12, in addition to 100 being passed through the dial 13, is inserted through poly-sided openings in a washer 15 which contacts with the inner side of the front wall of the casing 1, and through a disk 16 having in its peripheral edge a pair 105 of notches 17, while projecting longitudinally from the disk 16 away from the washer 15, is a rigid pin 18. Disposed on the cylindrical portion of the shaft 10 and in contact with the side of the disk 16 remote from the washer 15, is a second washer 110 19, while contacting with the side of this

washer remote from the disk 16, is a second and rotatable disk 16^a having in its peripheral edge a pair of spaced notches 17^a adapted at times to aline with the notches 17. In 5 addition to the notches 17^a, the disk 16^a is provided with an arcuate slot 18^a disposed concentric to the edge of said disk and receiving therein the pin 18, the slot in question being extended only throughout approximately a quarter of the circumference 10 of the disk for reasons to become obvious as the description proceeds.

In addition to the disk 16 which is immovable on the shaft 10, and the disk 16^a 15 which is rotatable thereon, an additional disk 16^b is rotatably mounted on said shaft and is spaced from the disk 16^a by a washer 20, the disk 16^b being provided in its peripheral edge with a pair of spaced notches 20 17^b adapted to aline with the notches 17 and 17^a for the purpose of allowing the teeth 7 of the neck 6 to drop into the same, whereupon when the shaft 10 is rotated by its head 11, the bolt 4 may be withdrawn. The means 25 for rotating the disk 16^b upon the shaft to properly position its notches 17^b, is constituted by the pin 18 which projects through the slot 18^a and into an additional and longer arcuate slot 18^b formed through the 30 disk 16^b concentric with the peripheral edge thereof.

Securing the several disks and washers, and the dial 13 in proper position upon the shaft 10, is a nut 21 disposed on the threaded end of said shaft, a washer 22 being 35 preferably interposed between the nut 21 and the innermost disk 16^b. By reference more particularly to Figs. 3 and 4, it will be observed that the shaft 10 continues beyond the nut 21 and that said shaft is here 40 reduced to provide a bearing journal 23 which is received by an appropriate bearing formed in one side of the casing 1.

When the several parts of the lock are 45 assembled as shown in Figs. 1, 2 and 3, a brake spring 24 bears against the alined peripheral edges of the three disks 16, 16^a and 16^b, thus frictionally locking the same against rotation until the shaft 10 is actuated in the proper manner to produce this 50 result. In so actuating the shaft, the knob 11 is turned to rotate said shaft until one of the numbered graduations on the dial 13 alines with the indicator 14. By this time, 55 the pin 18 has come into contact with one end of the slot 18^b and has thereby rotated the disk 16^b to the position shown in Fig. 4, thus disposing its pair of notches upwardly directly beneath the teeth 7. The 60 knob 11 is now rotated in the reverse direction, thus causing the pin 18 to strike one end of the slot 18^a, whereupon the disk 16^a will be rotated to dispose its notches 17^a in alinement with the notches 17^b, the proper 65 amount of rotation for this purpose being

ascertained by the dial 13 and the indicator 14. Needless to say, the brake spring 24 which has previously retained the disk 16^b in its adjusted position, now also frictionally locks the disk 16^a against rotation, while the 70 knob 11 is rotated again in the direction in which it was first turned, whereupon the pin 18 travels loosely within the slots to allow the disk 16 to be shifted the proper amount for alining its notches 17 with the previously 75 alined notches 17^a and 17^b. Needless to say, the position of the disk 16 is likewise disclosed to the legitimate operator of the lock by the relation of the dial 13 and indicator 14. 80

The moment the several pairs of notches are alined the spring 9 forces the entire inner end of the bolt downwardly and disposes the teeth 7 in said notches, whereupon turning of the knob 11 in the proper direction 85 will retract the bolt. When this has been done and the door or the closure equipped with the lock has been opened, the knob 11 is turned to such an extent as to allow the teeth 7 to be forced from the alined notches, 90 whereupon the spring 8 will again project the bolt. It will be obvious that the latter may be provided with the beveled end shown in the drawing whereby it will be automatically retracted when the closure is shut, or 95 that said bolt may have a square end, thus necessitating that it be retracted by its actuating means before the door or the like can be locked.

From the foregoing description, taken in 100 connection with the accompanying drawing, it will be evident that although extremely simple construction has been provided for carrying out the object of the invention, the complete lock will be highly efficient in operation and may be applied to a vast number of uses by making the necessary alterations falling within the scope of the invention.

I claim:

A lock comprising a shaft having at one 110 end an operating knob and at its other end a reduced journal, the portion of said shaft adjacent the knob being squared while the portion contiguous to the journal is externally threaded, a circular indicating plate 115 contacting with the knob and having a central square opening through which the squared portion of the shaft passes, an operating disk spaced from the indicating plate and likewise having a square central 120 opening receiving said squared portion of the shaft, a nut on the threaded portion of said shaft, a plurality of tumbler disks rotatable on the shaft between the nut and the operating disk, all of said disks having peripheral notches to be alined, and pick-up 125 disk operating means actuated by rotation of the operating disk; in combination with a casing having a side interposed between the indicating plate and operating disk, and an 130

additional side having a bearing in which the journal of the shaft is revolubly mounted, a locking bolt slideable in the casing and having a tooth for reception in the notches 5 of the disk when alined, a spring forcing said bolt normally toward the disks, and a single brake spring bearing against the peripheries of all of the disks.

In testimony whereof I have hereunto set my hand in presence of two subscribing wit- 10 nesses.

JOHN A. McCOACH.
